LOCOMOTIVE TENDER

Francis Hogg, Wesleyville, Pa., assignor, by
mesne assignments, to The Standard Stoker
Company, Inc., New York, N. Y., a corpora-
tion of Delaware

Application December 27, 1932, Serial No. 648,837

9 Claims. (Cl. 105—233)

This invention relates to locomotive tenders particularly constructed to receive a novel form of fuel pusher means for moving the fuel forwardly in the tender bin from the rear to the front 5 thereof, placing it within convenient reach of the fireman for delivering it to the locomotive firebox.

In apparatus of this type it has been customary to place the operating mechanism for the fuel pusher in the fuel bin at its upper rearward end.

10 One of the objects of this invention is to provide a novel tender and fuel pusher construction in which the pusher operating mechanism may be made more accessible and occupy no space in the fuel bin.

15 It is a further object of the invention to provide a novel fuel pusher and operating mechanism therefor that is simple in construction, compact in design and arrangement and efficient in operation.

20 Other objects and advantages of the invention will become apparent from the following description when read in connection with the accompanying drawings, in which

Fig. 1 is a central, longitudinal vertical section 25 of the forward portion of a locomotive tender with the invention applied thereto;

Fig. 2 is a sectional view taken on the line 2—2 of Fig. 1;

Fig. 3 is a central, longitudinal vertical section 30 of the forward portion of a locomotive tender with an alternative form of the invention applied thereto; and

Fig. 4 is a sectional view taken on the line 4—4 of Fig. 3.

35 On the drawings, referring more particularly to the preferred form of the invention illustrated in Figures 1 and 2, a locomotive tender is indicated generally at 10, comprising the fuel bin 11 and the water compartment 12, the two being 40 separated by the rear slope sheet 13, side slope sheets 14 and 15 and the fuel bin bottom wall or floor 16.

A coal pusher, generally indicated by the numeral 17, is mounted in the fuel bin 11 and arranged to reciprocate longitudinally over the surface of the rear slope sheet 13 and the fuel bin floor 16. The coal pusher 17 comprises a plurality of pusher heads, shown as four in number, and indicated respectively by the numerals 18, 45 19, 20, and 21. The pusher heads 20 and 21 which reciprocate over the surface of the fuel bin floor 16 are in tandem arrangement and rigidly connected together by the longitudinally extending tie plates 22 and 23. The pusher heads 18 and 50 19 which reciprocate over the surface of the rear

slope sheet 13 are flexibly connected together by a plurality of links 24 and similarly connected with the rigidly attached pusher heads 20 and 21.

The pusher heads are provided with an abrupt forward face 25 to carry fuel with them on their forward movement and a sloping back 26 permitting them to pass freely under the mass of fuel on their backward movement.

The rear slope sheet 13 is provided with a track 27 along which the pusher heads 18 and 19 reciprocate. Along the intersection of the side slope sheets 14 and 15 and the bin floor 16 there are secured in place in a suitable manner guide bars 28 and 29 forming with the floor 16 guideways 30 and 31 respectively. The tie plates 22 and 23 are 10 provided with the laterally extending flanges 32 and 33 respectively, arranged to be received in the guideways 30 and 31 respectively, permitting longitudinal sliding movement of the pusher heads 20 and 21, but preventing lateral and vertical movement.

The coal pusher 17 is operated by a reciprocating motor 34 which is rigidly secured to the underside of the floor 16 within the water tight compartment 35. The compartment 35 is formed 25 by the upright walls 36, 37 and 38 together with the tender frame 39 and floor 16 and is open at its forward end. The piston rod 40 is reciprocated longitudinally within the compartment 35 and beneath the floor 16 by the motor 34. At its forward end, the piston rod 40 is provided with a transversely extending arm 41, which is rigidly secured thereto and reciprocates therewith.

The tie plates 22 and 23 are provided with the depending flanges 42 and 43 respectively, which project through the longitudinal slots 44 and 45 respectively in the floor 16 of the fuel bin 11 and are secured in a suitable manner as by bolts 46 and 47 to the opposite ends respectively of the arm 41.

40 It is apparent therefore, that not only is there provided an unusually compact arrangement, but also the driving mechanism is conveniently located for purposes of inspection and repair and takes up no room in the fuel bin.

45 In Figures 3 and 4 there is shown an alternative construction in which the lower end of the rear slope sheet 13 is offset in a horizontal plane from the rearward end of the floor 16 forming an opening 48. A track 49 is mounted on the floor 16 and 50 extends rearwardly through the opening 48 beneath the rear slope sheet 13. A pusher member 50 is arranged to slide longitudinally along the track 49 but lateral and vertical movement is prevented. The pusher member 50 is flexibly 55

fastened with the pusher heads 18 and 19 in the same manner as in the preferred form of the device. A motor 51 for operating the pusher is mounted in the water tight compartment 52, 5 which is formed by the upright walls 53, 54, and 55 together with the floor 16 and tender frame 39. The motor 51 is shown mounted on the frame 39 but obviously could be mounted from the underside of the floor 16 as in the preferred form of the 10 device.

A bracket 56 is securely fastened to the upright wall 53 in the compartment 52 and a lever 57 is pivotally mounted intermediate its ends from the bracket 56. A pitman 58 connects one end of 15 the lever 57 with the pusher member 50 and a pitman 59 connects the other end of the lever 57 with the motor 51.

In this form of the device, a somewhat larger compartment is necessary to house the driving 20 mechanism than in the preferred form of the device but the advantages in other respects are the same.

I claim:

1. In a locomotive tender having a frame, a 25 water compartment and a fuel bin provided with a conventional substantially horizontal floor and a rear slope sheet, a coal pusher mounted in said bin, said pusher having one section mounted to reciprocate over the surface of said rear slope sheet and a section mounted to reciprocate over 30 said conventional floor, a forwardly opening water tight compartment at the forward end of the tender extending vertically from the tender frame to the said conventional floor, power means 35 in said compartment for operating said coal pusher, means connecting said power means to one of said coal pusher sections and means flexibly connecting the other of said coal pusher sections and said first named coal pusher section 40 whereby movement of said first named section by said power means is transmitted to said last named section.

2. In a locomotive tender having a frame, a water compartment and a fuel bin provided with 45 a conventional substantially horizontal floor and a rear slope sheet, a coal pusher mounted in said bin, said pusher having one section mounted to reciprocate over the surface of said rear slope sheet and a section mounted to reciprocate over 50 said conventional floor, a forwardly opening water tight compartment at the forward end of the tender extending vertically from the tender frame to the said conventional floor, power means 55 in said compartment for operating said coal pusher, means connecting said power means to said last named coal pusher section and means flexibly connecting said last named coal pusher section and said first named coal pusher section 60 whereby movement of said last named section is communicated to said first named section.

3. In a locomotive tender having a frame, a water compartment and a fuel bin provided with a conventional substantially horizontal floor, a reciprocable coal pusher mounted in said bin, a forwardly opening water tight compartment at 65 the forward end of the tender extending vertically from the tender frame to the said conventional floor drive mechanism in said compartment for said coal pusher supported from the 70 underside of said floor, and means passing through said conventional floor connecting said drive mechanism to said pusher.

4. In a locomotive tender having a frame, a water compartment and a fuel bin provided with 75 a conventional substantially horizontal floor and

a rear slope sheet, a coal pusher mounted in said bin to reciprocate over the surface of said floor and said rear slope sheet, a forwardly opening water tight compartment at the forward end of the tender extending vertically from the tender frame to the said conventional floor, drive mechanism for said coal pusher mounted in said compartment, and means passing through said horizontal conventional floor for connecting said drive mechanism and said coal pusher. 10

5. In a locomotive tender having a frame, a water compartment and a fuel bin provided with a conventional substantially horizontal floor and a rear slope sheet, a coal pusher mounted in said bin to reciprocate over the surface of said floor and said rear slope sheet, a forwardly opening water tight compartment at the forward end of the tender extending vertically from the tender frame to the said conventional floor, drive mechanism for said coal pusher in said compartment 15 and supported from the underside of said floor and means projecting through said floor for operatively connecting said coal pusher and said drive mechanism. 20

6. In a locomotive tender, a water compartment, a fuel bin comprising a rear slope sheet and a floor, a water tight compartment at the forward end of the tender beneath said fuel bin, said rear slope sheet and said floor at their adjacent ends being offset vertically forming an opening between said fuel bin and said water tight compartment, a coal pusher mounted in said bin, said pusher having one section mounted to reciprocate over the surface of said rear slope sheet and a section mounted to reciprocate over 30 said floor and through said opening, power means in said water tight compartment for operating said coal pusher and means connecting said power means to the section of said coal pusher reciprocable over said floor. 40

7. In a locomotive tender, a water compartment and a fuel bin provided with a floor and a rear slope sheet, a coal pusher mounted in said bin to reciprocate over the surface of said floor and said rear slope sheet, a water tight compartment at the forward end of the tender beneath said floor, said rear slope sheet and said floor at their adjacent ends being offset vertically forming an opening between said fuel bin and said water tight compartment, a reciprocatory motor mounted in said compartment, a lever pivotally mounted intermediate its ends at the rear of said water tight compartment and a pair of pitmans connecting the opposite ends of said lever with said pusher and said motor respectively for transmitting reciprocating motion from said motor to said pusher. 50

8. In a locomotive tender having a frame, a water compartment and a fuel bin, a conventional substantially horizontal floor and a rear slope sheet separating said water compartment and fuel bin, a coal pusher mounted in said bin, said conventional floor and rear slope sheet forming a fuel supporting surface over which the coal pusher is arranged to reciprocate, said pusher having one section mounted to reciprocate over the conventional floor portion of said fuel supporting surface and a section mounted to reciprocate over the rear slope sheet of said fuel supporting surface, a water tight compartment at 70 the forward end of the tender extending vertically from the tender frame to the said conventional floor, power means in said water tight compartment for operating said coal pusher, means projecting through said fuel supporting surface con- 75

necting said power means to the section of said coal pusher reciprocable over the conventional floor portion of said fuel supporting surface and means flexibly connecting said coal pusher sections whereby movement of the section reciprocable over the conventional floor is communicated to the section reciprocable over the rear slope sheet.

9. In a locomotive tender having a frame, a water compartment and a fuel bin provided with a conventional substantially horizontal floor and a rear slope sheet, a coal pusher mounted in said bin, said pusher having one section mounted to reciprocate over the surface of said rear slope

sheet and a section mounted to reciprocate over said conventional floor, a water tight compartment at the forward end of the tender beneath the fuel bin extending vertically from the tender frame to the said conventional floor, the rear wall of said compartment being forward of the upper half of said rear slope sheet, drive mechanism for said coal pusher mounted in said water tight compartment entirely beneath the level of the lower end of said rear slope sheet and means connecting said drive mechanism with the section of said coal pusher reciprocable over said conventional floor for operating the entire coal pusher.

FRANCIS HOGG.
